UNITED STATES PATENT OFFICE.

WILLIAM T. HUNTER, JUNIOR, OF WOODHAVEN, NEW YORK, ASSIGNOR TO A. SCHRAEDER'S SON, INCORPORATED, OF BROOKLYN, NEW YORK, A CORPORATION OF NEW YORK.

DUST CAP FOR TIRE VALVES OR THE LIKE.

Application filed December 17, 1914, Serial No. 877,709. Renewed July 14, 1921. Serial No. 484,820.

To all whom it may concern:

Be it known that I, WILLIAM T. HUNTER, Junior, a citizen of the United States of America, residing in Woodhaven, in the county of Queens and State of New York, have invented certain new and useful Improvements in Dust Caps for Tire Valves or the like, of which the following is a specification.

10 This invention relates to dust caps for tire valves or the like.

The usual form of tire valve is adapted to project through the wheel felloe to a greater or less degree, depending upon the thickness of the felloe. The standard form of dust cap hence may be found to be too short in a given case, or it may be unnecessarily long. According to the present invention I provide a dust cap which is capable of 20 extension and contraction, so that it may be elongated or shortened to fit the projecting portion of the valve. In the preferred construction the cap is made of a plurality of members which telescope one within the 25 other, so that shortening and elongation may be accomplished by mere adjustment of the outer shell. The invention includes certain other features which will be hereinafter more fully described.

20 Referring to the drawings,—

Figure 1 shows one embodiment of the invention in diametrical section.

Fig. 2 is an elevation of the parts detached.

25 Fig. 3 is a cross section on the line 3—3 in Fig. 1.

Fig. 4 is a diametrical section of another form of the invention in which the parts are inseparably connected.

30 Referring to the drawings, let A indicate a wheel felloe through which passes the valve B, the projecting end of which extends inwardly of the felloe. C is the improved dust cap, which, as shown, comprises a foot section D, and an end section E. The foot section D may be screw-threaded as shown at F to engage the valve, or may be adapted to engage any other part to hold it in place. In the construction 35 shown a washer G is swivelled to the foot of the cap, which washer may contain a packing such as H.

In the preferred form the end section E is imperforate at its outer end and is adapt-

ed to telescope with the foot section D. As 55 shown the end section is of slightly less diameter than the foot section and enters the upper portion of the latter.

The parts preferably move with considerable friction, so that the end section will 60 maintain its position without fastening devices. I prefer, however, to construct one of the parts with a series of spring arms, and in order to preserve the appearance of the device such arms are preferably formed 65 on the inner member. They are shown as formed by slitting the lower end of the end member E at various points as shown at J, and if desired small protuberances may 70 be formed in the arms as shown at K, which press outwardly into engagement with the outer member.

While the general shape of the cap may be round, hexagonal, or other form, it is preferred that some shape be adopted which 75 will not permit of relative rotation of the parts. In the construction shown a series of ribs L are formed on the cap, the ribs on the inner member being adapted to enter into the recesses or channels left in the formation of the ribs on the outer member. These ribs not only prevent rotation, but 80 act to stiffen the connection, so that a great degree of rigidity is imparted to it.

The provision of a non-rotative connection between the parts is of considerable importance, since it enables the dust cap to be 85 grasped by its outer end and screwed upon the valve stem, thus facilitating the application of the cap.

The parts may if desired be prevented entirely from separation, and in Fig. 4 is illustrated one method of accomplishing this result. In this figure the outer member D' is formed with an inturned flange M, while the 95 inner member E' is formed with an out-turned flange N. These flanges need not extend completely around the members, but may consist of a number of projecting parts if desired.

In the use of the device the cap will be 100 adjusted in length to suit the projecting portion of the tire valve. If such portion is unduly extended so that it reaches a considerable distance from the rim, difficulty may 105 sometimes be encountered in applying a cap of sufficient length because there is insufficient room between the wheel hub and the

end of the valve. With the present invention the cap can be contracted to its shortest dimensions when it is first applied and expanded as the foot is screwed home. Or in the case of the separable construction shown in Figs. 1 to 3 the foot portion can be first applied, and the end portion afterwards slid into place. In the last-named construction the cap also has the advantage that it is in effect a quickly detachable cap, inasmuch as the end section can be easily removed when it is desired to inflate or deflate the tire, or inspect the valve, the foot section remaining in place. By this means it is unnecessary to unscrew the foot section or provide any quickly detachable means between the foot section and the valve.

While the invention has been described with reference to a dust cap, it may be used in connection with other analogous devices.

While I have shown and described several forms of the invention, it will be understood that I do not wish to be limited thereto, since various changes may be made therein without departing from the spirit of the invention.

What I claim is:—

1. A dust cap comprising a plurality of telescopically connected parts extensible to vary the length of the cap, all of said parts having means for preventing relative rotation.
2. A dust cap comprising a plurality of telescopically connected parts, said parts being formed with coacting longitudinal ribs.
3. A dust cap comprising a plurality of telescopically connected parts extensible to

vary the length of the cap, all of said parts having means for preventing relative rotation, and being separable one from the other. 40

4. A tire valve cap having two parts, one of which is provided with an internal thread adapted to engage a thread of a valve stem and the other of said parts being adjustable lengthwise of the stem with regard to the first to assume different relative positions with regard to the first, in any of which positions the cap may be secured to the stem by screwing it along the threads of the latter, said parts being provided with a non-rotative connection whereby when the unthreaded part is rotated the threaded part is caused to rotate with it. 50

5. A dust cap for tire valves or the like comprising a plurality of telescopically connected parts formed with a plurality of faces for preventing their relative rotation and means on one of said parts for engaging a valve stem or the like to hold the cap thereon. 55

6. A dust cap for tire valves or the like, comprising a plurality of telescopically connected parts having means for preventing their relative rotation and spring means for holding said parts in any adjusted telescopic position. 60

In witness whereof, I have hereunto signed my name in the presence of two subscribing witnesses.

WILLIAM T. HUNTER, JUNIOR.

Witnesses:

E. G. MYERS,
FRED WHITE.

Certificate of Correction.

It is hereby certified that the name of the assignee in Letters Patent No. 1,488,924, granted April 1, 1924, upon the application of William T. Hunter, jr., of Woodhaven, New York, for an improvement in "Dust Caps for Tire Valves or the Like," should have been written and printed as *A. Schrader's Son* instead of "A. Schraeder's Son," as shown by the records of assignment in this office; and that the said Letters Patent should be read with this correction therein that the same may conform to the record of the case in the Patent Office.

Signed and sealed this 6th day of May, A. D. 1924.

[SEAL.]

KARL FENNING,
Acting Commissioner of Patents.
